UNITED STATES PATENT OFFICE.

SILAS TUTTLE, OF NEW YORK, N. Y.

DESIGN FOR A REGISTER-FAN.

SPECIFICATION forming part of Design No. 29,763, dated December 6, 1898.

Application filed November 11, 1898. Serial No. 696,181. Term of patent 7 years.

To all whom it may concern:

Be it known that I, SILAS TUTTLE, of New York, (Brooklyn,) Kings county, New York, have invented and produced a new and useful Design for Register-Fans, of which the following is a specification.

My design relates to the fans, vanes, or slats which are usually pivoted in registers through which hot air is admitted for heating purposes in buildings.

My design consists in the configuration of the slat, as hereinafter more particularly described.

The essential feature of my design consists in the cylindrical projections protruding from opposite edges of the fan and disposed axially in line and located at a greater distance from one longitudinal edge of the fan than from the other, together with a third projection parallel to one of the others and located between it and the nearest longitudinal edge of the fan.

Figure 1 is a side view, and Fig. 2 is an end view, of a slat exhibiting my design.

The slat is quadrangular in shape, having the edges C, parallel to the edges D, the ends E, parallel to the ends F, and the flat faces G and H. On the opposite ends E F appear cylindrical projections A B, so disposed that a line $x y$ drawn axially through the centers of both of them will be parallel to a longitudinal edge, as D or C, and nearer to the edge D than to the edge C. On the end F and parallel to the projection B and lying between said projection and the edge D appears a cylindrical projection I. The projection I, as appears in Fig. 2, is offset from the face G.

I claim—

The design for a register-fan substantially as herein shown and described.

SILAS TUTTLE.
